UNITED STATES PATENT OFFICE.

ALFONSO MERCER, SR., OF NORFOLK, VIRGINIA; W. W. MERCER ADMINISTRATOR OF
SAID ALFONSO MERCER, SR., DECEASED.

FIREARM.

1,308,017.

Specification of Letters Patent. Patented June 24, 1919.

Application filed May 2, 1918. Serial No. 232,101.

To all whom it may concern:

Be it known that I, ALFONSO MERCER, Sr., a citizen of the United States, residing at Norfolk, in the county of Norfolk and State 5 of Virginia, have invented certain new and useful Improvements in Firearms; and I do hereby declare the following to be a full, clear, and exact description of the invention, such as will enable others skilled in the 10 art to which it appertains to make and use the same.

This invention relates to firearms of various types for shooting projectiles from shells or the like, and relates particularly to 15 a clip or magazine adapted to be readily connected or attached to and detached from the firearm from which a load of cartridges or shells may be fired as successively fed thereto from the magazine.

20 It is one of the important objects of the present invention to provide a magazine or clip capable of holding a charge of cartridges of suitable size, shape and proportions, and to eliminate as far as possible the 25 likelihood of the jamming of the cartridges either in the magazine or clip, or at the breech block of the gun to which the clip may be attached.

It is another object of the present invention 30 to provide a simple, substantial, practicable and comparatively inexpensive magazine or clip for attachment to a gun of desired form or type, and further to provide means for automatically feeding the cartridges successively from a chamber in the 35 magazine in which the cartridges lie in laterally contacting arrangement. It is a further object of the invention to prevent the accidental disarrangement of a charge of 40 cartridges after the magazine has been filled.

A further object of the invention is to 45 provide a magazine or clip of large capacity and in which a series of cartridges may be safely concealed, and which clip is provided with means providing for facile attachment 50 of the clip to the gun or firearm, and which is provided with means for exposing a single cartridge in register with the bore of the gun or rifle and with means for precisely determining the alinement of a single cartridge 55 with the bore during the action of the piece.

With these and other objects in view as 60 will be manifest to those versed in the art, the invention consists in the construction, combination and in details and organiza-

tions of elements, as more particularly described in the following specification in reference to one embodiment of the invention, illustrated in the accompanying drawing, in which—

Figure 1 is a plan view partially in section of a rifle to which the clip is attached;

Fig. 2 is a cross section on the line 2—2 through the clip and rifle;

Fig. 3 is a detail sectional view showing 65 the means for connecting the clip or magazine to the firearm or piece.

While I have shown the improved magazine or clip as attached to a rifle having a barrel 2 and a breech block 3, it is obvious 70 that it may be adapted to various forms of firearms or ordnance pieces, it simply being necessary to design the magazine or clip to properly receive, contain and feed the cartridges or shells according to their specified 75 characteristics. In the present instance the breech block to which the barrel 2 is connected is provided with a reciprocating plunger or bolt 4, which may be reciprocated through any suitable means forming no part 80 of the present invention, and therefore not specified, illustrated or described, and within which bolt there is slidably a firing pin 5 which may be automatically projected by means of the spring 6 when released by any 85 suitable trigger mechanism.

A feature of the present invention resides in the magazine which is here shown as comprising a casing, generally illustrated at 10, 90 consisting of a segment or semicircle of an annulus, the bottom of the magazine being in the form of a plate 11 having at its diametrical edge a pair of laterally projecting lugs or tongues 12 which are adapted to be forced into respective seats or transverse 95 slots 13 provided to receive them in suitable locations of the gun structure, in the present instance being disposed below the bore of the barrel and as cut into the stock and casing structure of the gun. Preferably the tongues 100 12 fit with sufficient frictional resistance in the seats 13 as to insure the substantial holding in place of the clip or magazine when attached to the gun. The cartridge chamber is in the present instance shown as of flat 105 arcuate form and is formed between the upper surface of the plate 11 and the lower surface of a cover ring or segment of an annulus 14 spaced above the plate 11, the chamber being closed by an outer peripheral wall 110

15 so that the cover portion 14 projects centrally, and beyond its inner circular edge there is attached to the plate 11 an annular or segmental rib or ridge 16 spaced from the inner surface of the peripheral wall 15 a distance slightly greater than the length of the cartridges C which may be arranged radially in the chamber of the housing or casing.

- 10 At one end of the plate and the arcuate casing the plate is extended in the form of a lip 17 which enters an aperture provided therefor in the breech block and this lip has an upwardly extending stop or shoulder 18 which has a wall between the inner face of which and the adjacent open end of the chamber 10 there is formed a gateway at which the top plate of the chamber 10 terminates. This gateway is of a width slightly 15 greater than the width of a given cartridge so that while the magazine or clip is detached from the gun or piece, cartridges may be fed successively in the gateway and adapted to roll or slide laterally away from the shoulder or stop 18 and toward the adjacent face of a piston or push member 20 which sweeps with an angular movement through the chamber below the cover plate 14.
- 20 In the present case this piston or pusher 20 is shown as secured to the outer end of an arm 21 which is pivotally mounted to swing about axes at the center of the angular housing 10, in the present instance the arm 21 being pivoted on a fixed stud 22 and has a hub 23. The pusher arm 21 is adapted to be automatically advanced in one direction to press the piston 20 against a charge of 25 cartridges therein by any suitable means and for the purpose of illustration there is connected to the hub 23 of the arm 21 a spiral or volute spring 24 having its end fixed as for instance by a pin 25 to the plate 11, although it is obvious that any other type of 30 spring may be utilized as may be desired or preferred. The outer end of the arm swings just above the top surface of the ridge or rib 16 forming the bottom of the chamber in the housing 10 and may be bent downwardly 35 at right angles if desired where it is attached to the inner end of the piston 20 which latter preferably snugly fits in the chamber of the housing 10 so as to firmly support the adjacent cartridge of a series which has been 40 loaded into the magazine.
- 45 When loading the magazine the operator simply presses the piston 20 back against the tension of its actuating spring and one at a time lowers cartridges in through the gateway at the stop 18, the cartridges passing beneath the top 14 of the chamber and sliding into lateral contact against each other until the entire arcuate chamber has been 50 filled with a series of cartridges which form an arcuate row about the center 22 and each

55 of the cartridges lying in a substantially radial position to the center 22, the entire series lying in a common plane on top of the plate 12 of the magazine. As soon as the operator releases control of the pusher or piston 20, the latter automatically swings into contact with the adjacent cartridge and compresses the entire series with lateral compression so that the cartridges are forced 60 against each other side to side with the first of the cartridges being advanced into the gateway at the block 18, which gateway when the clip is attached to the firearm disposes the cartridge therein in axial alinement with the bore of the firearm or piece, whereupon 65 by forward movement of the bolt 4, a single cartridge is advanced into the firing chamber of the barrel and may be fired by the firing pin at any suitable instant.

70 Withdrawal of the block causes the extraction of the cartridge in any suitable or usual manner whereupon the next succeeding cartridge in the magazine chamber is projected into the gateway as the bolt recedes through the gateway and the loading action 75 may be then again repeated.

80 In order to prevent disarrangement of a series of cartridges in the magazine chamber from any cause, the automatic feeding device, including the piston 20, is held 85 against retrograde movement by any suitable and appropriate means, comprising in the present instance a locking pawl 28 which is pivoted on the outer end of the lever arm 21 and is automatically snapped into locking engagement with respective ratchet teeth 29 which may be formed for instance on the upper face of the rib or ridge 16, forming one side wall of the magazine chamber, by a spring 30. To enable the loading 90 of the magazine, one end of the latch 28 may be provided with a push button 31, which when pressed downwardly, will hold the pawl 28 from engagement with the ratchet teeth 29.

95 While it is obvious that this clip may be attached to extend longitudinally along the barrel at any circumferential position about the same, preferably it is designed to be attached to the left hand side of the barrel to 100 extend laterally therefrom with the plate 11 in a plane extending along or parallel to the barrel 2. Obviously the actuating spring 24 will be proportioned so as to give the desired 105 pressure against the series of cartridges and to successively feed the cartridges of a load or series which may have been inserted into the cartridge chamber.

110 What is claimed is:—

- 115 1. A detachable magazine for fire-arms or the like, consisting of a flat, arcuate cartridge chamber in which cartridges lie in lateral contact, and radially as to the center of the arc, the chamber having at one end a gateway adapted to be inserted into the case 120

125 130

- of the fire-arms and alined with the bore of the barrel so that the plunger of the arm will traverse the gateway, means for attaching the magazine to the arm with the 5 plane in which the cartridges lie passing longitudinally through the bore of the arm, and means for advancing the cartridges successively into the gateway from the chamber.
- 10 2. A magazine for fire-arms or the like, consisting of an arcuate, flat casing having a segmental chamber in which the cartridges lie in radial order and laterally in contact in a common plane, one end of the casing having 15 a gateway insertible into the arm and across the gun bore so that cartridges may be advanced therefrom by the bolt of the gun, and automatic means for moving the cartridges edgewise into and in the plane in 20 which the cartridges rest in the chamber of the magazine.
3. A magazine for firearms or the like, consisting of a segmental casing having a flat, segmental cartridge chamber terminating 25 at one end in a gateway insertible into the side of the arm, means for connecting the casing to an arm with the gateway so disposed as to aline a cartridge therein with the bore of the arm, and yieldable means for 30 automatically feeding the cartridges laterally through the chamber and into the gateway, the cartridges lying radially in an arc and in a plane of the axis of the bore.
4. A magazine for firearms or the like, 35 consisting of a stationary segmental casing having a plane arcuate cartridge chamber terminating at one end in a gateway in the plane of the chamber, means for connecting the casing to a firearm with the gateway so disposed as to aline the latter with the bore of the arm, means operating along the chamber for automatically feeding the charge of cartridges laterally through the chamber and into the gateway and without digressing 45 from the plane of the chamber, and means for locking the feeding means at successive positions thereof.
5. A magazine for firearms or the like, 50 consisting of a segmental casing having a flat arcuate cartridge chamber, in which cartridges lie radially terminating at one end in a gateway substantially radial to the
- chamber, means for connecting the casing to an arm with the gateway so disposed as to aline a cartridge therein with the bore 55 of the arm, means for automatically feeding the charge of cartridges laterally through the chamber and into the gateway, said means comprising an angularly movable piston, and a spring for actuating it, 60 the cartridges always lying in a common plane.
6. The combination with a firearm having a breech casing with a plunger and firing pin; of a magazine detachably connectible and fixed stationary to the side of the arm and having a flat arcuate chamber, for a charge of cartridges, terminating in a gateway registrable with the gun bore and through which gateway the said plunger 70 works to load the arm from the gateway, and means on the magazine for automatically laterally advancing the cartridges in the chamber.
7. The combination with a firearm having a breech casing with a bolt and firing pin, of a magazine detachably connectible to the side of the arm and having an arcuate chamber, for a charge of cartridges, the magazine having a gateway registrable with 80 the gun bore and through which the said bolt works to load the arm from the gateway, and means on the magazine for automatically laterally advancing the cartridges in the chamber, said means including a 85 radial lever swinging on the axis of the arc of the chamber and having a piston on its outer end engaging the last of the series of cartridges in the magazine, and a device for actuating the lever.
8. The combination with a firearm having a breech casing with a bolt and firing pin, of a magazine detachably connectible to the side of the arm and having an arcuate chamber, for a charge of cartridges, terminating 95 in a gateway registrable with the gun bore and through which the said plunger works to load the arm from the gateway, means on the magazine for automatically laterally advancing the cartridges in the chamber, and 100 a locking device to prevent recession of said means.

In testimony whereof I affix my signature.
ALFONSO MERCER, Sr.
